UNITED STATES PATENT OFFICE.

EDWIN DE HAVEN CALDWELL, OF GENEVA, ILLINOIS, ASSIGNOR OF ONE-HALF TO JOHN B. WILSON, OF GENEVA, ILLINOIS.

LUBRICATING APPARATUS FOR ENGINES.

SPECIFICATION forming part of Letters Patent No. 763,719, dated June 28, 1904.

Application filed December 5, 1903. Serial No. 183,900. (No model.)

To all whom it may concern:

Be it known that I, EDWIN DE HAVEN CALDWELL, a citizen of the United States, residing at Geneva, county of Kane, and State of Illinois, have invented certain new and useful Improvements in Lubricating Apparatus for Engines, of which I do declare the following to be a full, clear, and exact description, reference being had to the accompanying drawings, forming part of this specification.

The present invention is designed more particularly to provide an improved lubricator for the cross-heads of engines; and the invention consists in the features of improvement hereinafter described, illustrated in the accompanying drawings, and particularly pointed out in the claims at the end of this specification.

Figure 1 is a view in elevation of an engine having my invention applied thereto. Fig. 2 is an enlarged detail view, in vertical longitudinal section, of the lubricating apparatus embodying my invention.

My invention is shown as applied to a stationary engine of the simple expansion type, although manifestly it is susceptible of application in a variety of other situations. The frame A of the engine is provided with usual guides B, in which travels the cross-head C, that is connected by a wrist-pin d with a connecting-rod E, which leads to the crank F of the engine.

My improved lubricator in the preferred form of the invention comprises a cylinder G, that is conveniently attached to some part of the engine-frame. Preferably the cylinder G has cast in piece therewith or attached thereto an arm or bracket g, that is provided with one or more slots g', through which will pass bolts g'', that will enter threaded holes tapped in the engine-frame. The slots g' will be sufficiently long and preferably, also, of considerably-greater width than the diameter of the bolts g'' to permit of the adjustment of the cylinder to the required position upon the engine-frame, it being understood that the heads of the bolts g'' or washers carried thereby will be larger than the slots g'. The cylinder G is connected at one end by a pipe h

with an oil cup or reservoir H, this oil cup 50 or reservoir being of any suitable type—such, for example, as the ordinary sight-feed cup. Preferably the rear end of the cylinder G is fitted with a diaphragm G', forming a small chamber G² at the rear end of the cylinder in 55 which a certain head of oil may accumulate. The diaphragm G' is fitted with a suitable valve, and preferably this valve consists of a disk i at the end of a stem I, that passes through the hole in the diaphragm G', through 60 which the oil escapes from the chamber G² to the cylinder. The rear end of the stem I passes through a hub g⁴ at the back end of the cylinder G and is encircled by a coiled spring J, the outer end of which bears against a head 65 j, carried by the stem I. This coiled spring J thus serves to hold the valve i normally closed, so as to prevent the flow of oil through the diaphragm G'. Preferably a cap K 70 encloses the spring J, the threaded inner end of this cap engaging corresponding threads upon the hub or boss g⁴ at the rear end of the cylinder G. It is obvious that any other suitable form of check valve mechanism may be used between the body of the cylinder and 75 the oil cup or reservoir, although I prefer the arrangement described, as the provision of the supplemental chamber G² insures the head of oil in readiness to be delivered to the interior of the cylinder G. 80

Within the cylinder G is mounted in manner free to slide a piston L, that is carried at the inner end of a tubular piston-rod M, the bore m of this piston-rod opening through the inner face of the piston L and affording a 85 channel for the passage of oil from the interior of the cylinder G. A snug fit of the piston L with the interior of the cylinder G may be insured by a cup-leather L' or in any other suitable manner. The piston-rod M passes 90 through the outer end or head G³ of the cylinder G, this head being preferably connected by flanges to the cylinder, as shown. Around the piston-rod M sets a coiled spring M', one end of which bears against the head G³ of the 95 cylinder, while its opposite end bears against the head N of the piston-rod M, through which head N a passage m of the piston-rod extends.

Preferably the outer face of the piston-rod head N is fitted with a perforated leather disk n, that may be conveniently held in place by a steel ring n', secured to the outer face of the piston-rod head.

- Opposite the piston-rod head N is mounted the plunger P, from which a tubular stem or pipe p extends to the cross-head B or other moving part of the engine to be lubricated.
- 10 The stem p of the plunger P may be attached to the cross-head at any convenient point and in any suitable manner, and it will be understood that from the inner end of the stem or pipe p suitable channels will lead through the
- 15 wrist-pin to the guides or other parts to be lubricated. Preferably the outer face of the plunger P is provided with a circular offset or raised portion p', adapted to enter within the ring n' of the piston-rod head N and bear
- 20 firmly against the leather disk on the outer face of the piston-rod head. In the preferred form of the invention the piston-rod head N is provided with a ball-valve R, (or other suitable check-valve,) held normally against its
- 25 seat r by a light spring r', the opposite end of this spring bearing against a ring r², and preferably also a similar check-valve S is provided in the plunger P or in the pipe leading therefrom to the cross-head.
- 30 From the foregoing description the operation of my improved lubricating apparatus will be seen to be as follows: As the cross-head B reciprocates, the plunger P will contact with the piston-rod head N, making a tight
- 35 joint therewith and forcing the piston-rod head, the piston-rod, and the piston inward against the spring M'. As the piston L is thus forced inward, the oil within the body of the cylinder G will be caused to flow through
- 40 the channel m of the piston-rod and, unseating the valves R and S, will pass through the piston-rod head N, the plunger P, and the stem or pipe p to the cross-head of the engine. As the engine cross-head moves in opposite
- 45 direction, carrying with it the plunger P, the spring M' forces outward the piston-rod head N and the piston L, and this outward movement of the piston L causes the valve i to be unseated, thereby permitting oil to flow from
- 50 the supplemental chamber G² into the interior of the cylinder G and permitting the ball-valves R and S to be returned by their springs to their respective seats. It will thus be seen that at each stroke of the cross-head a quantity of oil will be delivered thereto. It will be understood that the piston-rod M fits sufficiently loosely within the head G³ of the cylinder to prevent the formation of an air suction at the outer end of the cylinder, or, if
- 55 desired, the cylinder-head G³ may be formed with a vent-hole for such purpose.

My improved lubricating apparatus presents many advantages over devices heretofore employed. The oil is delivered to the

60 cross-head under pressure and a predeter-

mined quantity of oil is delivered at each stroke of the cross-head, so that waste of the oil is avoided. Inasmuch as the piston L draws or sucks the oil into the cylinder G, it is manifest that the reservoir or supply for oil may be set at any desired level either above or below the cylinder G. The slight pressure of air caused by the entrance of the offset portion of the plunger P into the ring n' on the outer face of the piston-rod head serves to unseat the valves R and S, so that the passageway from the cylinder to the cross-head is open for the injection of the oil as the piston-rod head and piston are forced inward.

So far as I am aware my present invention presents the first instance of a lubricating apparatus in which there is combined a receptacle for oil, a movable head or member, the shift of which is adapted to force oil from said receptacle and though said head, and a plunger adapted to shift said movable head or member and provided with a channel or passage for leading the oil from the plunger toward the part to be lubricated, and I wish the invention, as hereinafter claimed, to be understood as covering, broadly, such a lubricating apparatus without regard to the details of structure employed in its practical embodiment, since manifestly such details of structure may be varied within wide limits without departing from the spirit of the invention.

Having thus described my invention, what I claim as new, and desire to secure by Letters Patent, is—

1. A lubricating apparatus comprising a receptacle for oil, a movable head or member provided with means for forcing oil from said receptacle and having an opening through which the oil is forced, a plunger separate from said movable head or member and connected to a movable part of the engine and arranged in position to shift said movable head or member, a tube connected to and movable with said plunger for conducting the oil from said plunger and means for restoring said head or member to normal position as the plunger recedes therefrom.

2. A lubricating apparatus comprising a cylinder for containing oil, a piston within said cylinder, a tubular rod connected to said piston and provided with an open head or end through which oil will be discharged, a plunger adapted to be connected to a movable part of the engine and having an opening through it for the passage of oil from said tubular rod, and a tube for conducting the oil so received to the point to be lubricated.

3. A lubricating apparatus comprising a receptacle for oil, a piston within said receptacle, a tubular rod leading outward from said piston and provided with an open head or end, a tube adapted to be connected to a movable part of the engine and provided with a head or end arranged in position to contact with the head or end of said tubular rod and to receive

oil therefrom, said tube serving to conduct the oil to the point to be lubricated.

4. A lubricating apparatus comprising an oil-receptacle, a movable head or member whereby oil is forced from said receptacle, a pipe leading from said oil-receptacle for the discharge of oil, a tube connected to a movable part of the engine and serving to deliver oil to the part to be lubricated, said pipe and said tube being provided at their opposing free ends with parts adapted to form a tight joint to permit oil to pass from said pipe to said tube.

5. A lubricating apparatus comprising an oil-receptacle, a piston within said oil-receptacle having a tubular stem or rod through which oil will be forced, in combination with a plunger connected to a movable part of the engine, a tube leading from said plunger and movable therewith for conducting the oil therefrom, the outer end of said piston-stem being located in the path of travel of said plunger and adapted to be shifted thereby to cause the oil to be forced from said receptacle.

25 6. A lubricating apparatus comprising a cylinder, means for delivering oil to said cylinder and means for forcing oil from said cylinder comprising a piston, a tubular rod leading from said piston and provided with a perforated head, a spring for moving said rod and piston in one direction, a plunger connected to a movable part of the engine and arranged to shift said head and piston in the opposite direction, and a tube for conducting the oil from said perforated plunger.

7. A lubricating apparatus comprising a cylinder provided at one end with a supplemental chamber, means for delivering oil to said supplemental chamber, a valve for controlling the flow of oil from said supplemental chamber to said cylinder and means for forcing oil from said cylinder comprising a piston, a movable head or member connected to

said piston and provided with a passage through which oil passes from said cylinder, a plunger connected to a movable part of the engine and arranged in position to shift said movable head or member, a tube for conducting the oil from said plunger, and means for restoring said movable head or member and said piston to normal position as the plunger recedes therefrom.

8. A lubricating apparatus comprising a receptacle for oil, a movable head or member provided with means for forcing oil from said receptacle, said head or member having an opening therein through which the oil is forced, a plunger connected to a movable part of the engine and arranged in position to shift said movable head or member, said head or member and said plunger being formed, one, with an annular raised rim, and the other with a projecting part adapted to enter said annular raised rim, a tube for conducting the oil from said plunger and means for restoring said movable head or member to normal position as the plunger recedes therefrom.

9. A lubricating apparatus comprising a cylinder, means for delivering oil to said cylinder and means for forcing oil from said cylinder comprising a piston located in the cylinder, a movable head or member and a tubular rod connecting said head or member to said piston, a coil-spring encircling said tubular rod for forcing said head or member normally outward, a plunger connected to a movable part of the engine and arranged in position to shift said movable head or member, and a tube for conducting the oil from said plunger.
